[57] ABSTRACT

A process and apparatus for assembling a container

having first and second sections, the first section having a bottom and a side wall with flaps thereon and a second section having another side wall and lateral end walls thereon. A plurality of rigid skids are secured to the bottom wall of the first container section. The apparatus includes a skid positioning station, a first gluing station, a mechanical fastening station, a second gluing station, and a pressure applying station. A first conveyor transfers a plurality of skids from the skid positioning station to the mechanical fastening station. During this transfer, adhesive is applied to the upper surface of each of the skids. The first container section is placed over the skids and thereafter, means are provided for applying at least one mechanical fastener into each skid and through the first container section, while both are stationary, to thereby mechanically secure each skid to the container section. A second conveyor means then transfers the partially mechanically fastened skids and first container section simultaneously past the second adhesive applying station and to the pressure applying station. During movement to the pressure applying station, adhesive is applied to the upper surface of the flaps of the first container section. Means are provided for stopping the skids and the first container section and the second container section is positioned in such a way that portions of the second container section overly the flaps with adhesive thereon. Mechanical pressure is then applied to the flaps and overlying portions of the second section for adhesively bonding the two container sections together.

PROCESS AND APPARATUS FOR ASSEMBLING A BULK CONTAINER

BACKGROUND OF THE INVENTION FIELD OF THE INVENTION and DESCRIPTION OF THE PRIOR ART

This invention relates to a process and apparatus useful for assembling a container having two container sections with a plurality of rigid skids mounted on the underside thereof.

The container shown in Heavner U.S. Pat. No. 3,743,166 and the pallet type container shown in patent application Ser. No. 240,975, filed Apr. 4, 1972, by Larry W. Heavner, both relate to pallet type containers wherein the pallet structure is a unitary part of the container. Prior to such constructions it was the common practice in shipping of articles, in bulk, to attach the heavy cardboard container to a suitable pallet, generally made of wood, for supporting the container and articles carried therein for convenient handling by a fork lift truck or like material handling equipment. Usually, the wooden pallets are mechanically attached to the container bottom by staples, nails, and sometimes by banding the container to the pallet. One of the principal drawbacks of these prior art constructions is the high cost involved in the manufacture and the labor involved in the use of these wooden pallets and in similar alternate constructions.

For the most part, containers such as shown in the said Heavner patent and in the said Heavner application have been manually assembled from corrugated cardboard blanks and the skid portions have been manually secured to the bottom of the container. The manual assembly of these containers is particularly difficult because of the large size of the blanks. For example, the type of container shown in the Heavner application is constructed from two sections with one section having a bottom wall and a side wall with two lateral flaps thereon. This section can be as large as 8 inches $\times$ 8 inches. The second container section before securement to the first container section, can be as large as 8 inches $\times$ 17 inches. Needless to say, the manual handling of corrugated blanks of this size is cumbersome. In addition, at least two or three wooden skids, or the like, must be secured to the bottom wall of the first container section. Any method and apparatus wherein the skids can be secured to the first container section and wherein the two container sections may be secured together with minimal manual handling, and in a convenient, efficient and time saving manner, would be highly desirable.

SUMMARY OF THE INVENTION

It is therefore an important object of this invention to provide a unique apparatus and process for the assembling of a bulk container of the type having pallet type skids rigidly secured to the bottom wall of the container.

It is also an object of this invention to provide a method and apparatus for assembling rigid skids to a first container section, and thereafter, assembling a second container section to the first section, in order to form a unitary "knock down" bulk, pallet type container.

It is a further object of this invention to provide a unique apparatus for assembling a bulk container comprised of two container sections having skids on the bottom thereof, wherein the apparatus is particularly

characterized by its simplicity and economy of construction and efficiency in operation.

It is still another object of this invention to provide a unique method and apparatus for efficiently securing a plurality of rigid support members to a single container member and thereafter simultaneously moving all the members while the mechanical securement of the members to the single member is completed.

Further purposes and objects of this invention will 10 appear as the specification proceeds.

The foregoing objects are generally accomplished by an apparatus and method for assembling a container of the type which has first and second container sections, the first container section having a bottom wall and a 15 side wall with flaps thereon, the second container section having another side wall and lateral end walls thereon, and a plurality of rigid skids being secured to the underside of the bottom wall; the apparatus and method includes a skid positioning station, a first gluing 20 station, a mechanical fastening station, a second gluing station and a pressure applying station. A transfer mechanism carries the skids from the skid positioning station to the mechanical fastening station, while means are provided for applying adhesive to the upper 25 surface of the skids during the transfer of the skids to the mechanical fastening station. Initially, at least one mechanical fastener is used to secure each skid to the undersurface of the first container section, while the skids and first section are stationary. The conveyor 30 thereafter conveys the mechanically fastened skids and first container section past the second adhesive applying station and to the pressure applying station, while the second adhesive applying station is applying adhesive to the upper surface of the flaps. Means are provided for stopping and aligning the first and second 35 container sections with portions of the second container section overlying the flaps with the adhesive thereon. Means thereafter apply mechanical pressure to the flaps and overlying portions of the skid section 40 for adhesively bonding the two container sections together to form a completely assembled container.

BRIEF DESCRIPTION OF THE DRAWINGS

A particular embodiment of the present invention is 45 illustrated in the accompanying drawings wherein:

FIG. 1 is a top plan view of the front half of the machine used for assembling a plurality of skids to the underside of a first container section and for thereafter assembling a second container section to the first container section;

FIG. 1a is a continuation of FIG. 1, illustrating the rear half of the machine shown in FIG. 1;

FIG. 2 is a side elevational view of the embodiment of the front half of the machine shown in FIG. 1;

FIG. 2a is a side elevational view of the rear half of the machine shown in FIG. 1A;

FIG. 3 is a partially broken, top plan view of a counter mechanism used for applying staples through the first container section and into the skids;

FIG. 4 is a side elevational view of the embodiment of FIG. 3;

FIG. 5 is a rear end elevational view of the machine of FIGS. 1, 1a, 2 and 2a, as viewed from the right end of FIG. 2a;

FIG. 6 is a transverse sectional view taken along the line 6—6 of FIG. 2, illustrating the mechanical fastener applying station;

FIG. 7 is an enlarged, partially broken, detail view in end elevation of a stapling mechanism used in the machine of FIGS. 1, 1a, 2 and 2a;

FIG. 8 is an enlarged sectional view taken along the line 8—8 of FIG. 6 illustrating the vertical guide and support means for the mechanical fastening section;

FIG. 9 is a side elevational, sectional view taken along the line 9—9 of FIG. 7 showing the stapling mechanism and stop mechanism in side elevation;

FIG. 10 is a sectional, detail view of a portion of the support frame for the stapling mechanism shown in FIG. 9;

FIG. 11 is a sectional view taken along the line 11—11 of the embodiment of FIG. 10;

FIG. 12 is an end elevational view of the stop mechanism illustrated in FIG. 9;

FIG. 13 is a detail, top plan view of the transfer mechanism used for transferring a skid from the skid positioning station and past the first adhesive applying station;

FIG. 14 is a side elevational view of the embodiment of FIG. 13;

FIG. 15 is an enlarged sectional view taken along the line 15—15 of FIG. 14;

FIG. 16 is an enlarged, detail view, as viewed along the line 16—16 of FIG. 1, of the limit switches and glue applying means for applying glue to the skids;

FIG. 17 is a top plan view of the embodiment of FIG. 16;

FIG. 18 is a detailed, side elevational view of the mechanism for applying glue to the flaps of the first container section;

FIG. 19 is a top plan view of the embodiment of FIG. 18;

FIG. 20 is an enlarged, side elevational, detailed view, as viewed along the line 20—20 of FIG. 1, illustrating the cam and conveyor arrangement used in the transferring of the first container section and skids to the second glue applying station and to the pressure applying station;

FIG. 21 is a top plan view of the embodiment of FIG. 20;

FIG. 22 is a sectional view taken along the line 22—22 of the embodiment of FIG. 20;

FIG. 23 is an enlarged detailed view, as viewed along the lines 23—23 of FIG. 1a, of the opposite end of the conveyor mechanism shown in FIGS. 20—22;

FIG. 24 is a top plan view of the embodiment of FIG. 23;

FIG. 25 is a sectional view taken along the line 25—25 of FIG. 23;

FIG. 26 is a side view of the embodiment illustrated in FIG. 25;

FIG. 27 is an end elevational, detail view of the stop mechanism at the pressure applying station of the machine;

FIG. 28 is an end elevational view of the embodiment of FIG. 27;

FIG. 29 is a detail view of a portion of the frame of the machine;

FIG. 30 is another detail view illustrating the frame of the machine;

FIG. 31 is a further view illustrating the frame of the machine;

FIG. 32 is a side elevational, schematic view of the skid positioning station of the machine;

FIG. 33 is a top plan view of the embodiment of FIG. 32;

FIG. 34 is a side elevational, schematic view of the mechanical fastening section of the machine;

FIG. 35 is a top plan view of the embodiment of FIG. 34;

FIG. 36 is a top plan view illustrating the second glue applying station and the support for the second container section;

FIG. 37 is a top plan view of the embodiment of FIG. 36;

FIG. 38 is a side elevational view of the pressure applying station of the machine;

FIG. 39 is a top plan view of the embodiment of FIG. 38;

FIG. 40 is a perspective view of the two container sections with skids attached thereto while being moved to the assembled condition; and

FIG. 41 is a perspective view from the bottom side of an assembled bulk container.

DETAILED DESCRIPTION OF THE PREFERRED EMBODIMENT

Referring to FIGS. 40 and 41, there is shown one preferred assembled container, generally 10, which is constructed by our method and apparatus for assembling bulk carton containers. The container 10 shown in the drawings is the type shown in U.S. Pat. application Ser. No. 240,975, filed Apr. 4, 1972, by Larry W. Heavner. Although the method and apparatus to be described herein will specifically relate to the manufacture and assembly of the container 10, it is to be understood that the described method and apparatus are also useful in connection with the manufacture of other similar types of containers, and furthermore components of the apparatus and steps of the described process may well be used in connection with the manufacture and assembly of other types of containers.

Referring to FIGS. 35, 40 and 41, the container 10 is comprised of a first container section, generally 12, and a second container section, generally 14. Referring to FIG. 35, the first container section includes a bottom wall 16, a side wall 18, flaps 20 hingedly secured to the side wall 18, and a top flap 22 which is hingedly connected to the side wall 18. The second container section 14, as seen best in FIGS. 39—41, includes a pair of end walls 24, a side wall 26, a top flap 28, a bottom flap 30, a pair of top end flaps 32, and a pair of bottom end flaps 34. A plurality of rigid skids 36, made from wood or other rigid material, are rigidly secured to the outer face of the bottom wall 16 of the first container section 12. The inventive method and apparatus are directed to the assembly of the container 10 wherein the two container sections 12 and 14 are assembled together and the skids 36 are assembled to the first container section 12.

I. THE CONTAINER ASSEMBLY METHOD

The method for assembling the container 10 can best be understood by referring to FIGS. 32—39, which schematically illustrate the steps comprising the inventive method. The apparatus, generally 38, which will be described in detail hereinafter by referring to FIGS. 1—31, includes a skid positioning or loading station, generally 40, a first adhesive applying station, generally 42, a mechanical fastening station, generally 44, a second

adhesive applying station generally 46, and a pressure applying station, generally 48.

Referring to FIGS. 32 and 33, the rigid wooden skids 36 are first located or manually positioned at the skid loading station 40 of the apparatus 38. In FIG. 32, the skids are shown in side elevation while in FIG. 33, the skids 36 are shown in top plan view. A plurality of skids 36 are used in order to provide suitable support for the bottom wall 16 of the first container section 12 since the container 10 is constructed to receive heavy articles, for example, automobile engine blocks.

After the rigid skids 36 are manually positioned at the skid loading station 40, they are conveyed or transferred past the first adhesive applying station 42. At the adhesive applying station 42, adhesive is applied to the upper surface of each of the skids 36. Any suitable adhesive useful for securing wood to cardboard or paper can be used, such as an epoxy or other type of cold setting adhesive.

Referring to FIGS. 34 and 35, the skids 36 are transferred to the mechanical fastening station 44 from the skid loading station 40. The movement of the skids 36 from the skid loading station 40 and past the adhesive applying station 42 is stopped momentarily at the mechanical fastening station 44. The first container section 12 is laid or positioned over the skids 36. Specifically, the bottom wall 16 is positioned over the skids 36 because the skids 36 provide rigid support for heavy articles, as engine blocks, to be shipped within the container 10. In the embodiment shown, three skids 36 are used. The first container section 12 is positioned so that the lateral ends of the bottom wall 16 are generally aligned with the outer edges of the outer pair of skids 36, while the central skid 36 is positioned substantially intermediate the outer skids 36.

After the first container section 12 has been properly positioned over the skids which have had adhesive applied thereto, a mechanical fastener, as a staple, is driven through the bottom wall 16 and into the leading portion of each of the skids 36. This is an important aspect of the described method so that a plurality of skids 36 and the container section 12 may be easily moved simultaneously for further processing. Although adhesive has been applied to the upper surface of the skids 36, a mechanical fastening of the skids to the container section is highly desirable in order to hold the skids and container sections together for a sufficient period of time for the adhesive to set and firmly bond portions of the bottom face of the bottom wall 16 to the skids. The single staple, nail, or other type of mechanical fastener, which is driven through the container section 12 and into the leading edges of each of the skids 36 enables the desired simultaneous movement of the first container section 12 and attached skids 36.

Once each of the skids 36 has been properly secured by one mechanical fastener to the first container section 12, the first container section 12, and the assembled skids 36 are carried towards the pressure applying station 48. During this transfer, a plurality of spaced mechanical fasteners, such as staples or nails, are sequentially driven through the bottom wall 16 and into each of the skids 40 in order to provide firm mechanical securement between the bottom wall 16 and the rigid skids 36. Not only do the mechanical fasteners provide mechanical securement between the skids and the container section, but they also cooperate with the

set adhesive to provide an exceptionally strong bond between the skids and the first container section.

Referring to FIGS. 36 and 37, the mechanically assembled skids 36 and first container section 12 are carried along the same path of travel and past the second adhesive applying station 46. At this station, adhesive is applied to the upper face of the flaps 20 connected to the side wall 18 of the first container section 12.

As seen in FIG. 36, the second container section 14 is generally aligned and supported above the first container section 12 at the second adhesive applying station 46. Adhesive which is applied at the second adhesive applying station 46 is provided for joining the container sections 12 and 14 together.

After the adhesive has been applied along the upper face of the flaps 20 of the first container section 12, the second container section 12 is positioned so that a folded outer surface portion of the end wall 24 is aligned above and adjacent each of the flaps 20 which have adhesive thereon. When the outer edge of the side wall 26 is thus positioned, movement of the first container section 12 ceases and mechanical pressure is applied at the pressure applying station 48 along the entire area of contact between the flaps having the adhesive or glue thereon and the adjacent outer edge of the end walls 24 of the second container section 14. Pressure is applied for a period of time sufficient to permit adhesive to bond the two container sections together when a suitable adhesive, preferably a resin type of adhesive is used. About ten seconds is generally sufficient for obtaining a sufficient bond between the two container sections to enable further handling of the container 10, when for example, a conventional resin adhesive is used.

It is seen from the foregoing that our process for assembling the container 10 is simple, effective, and requires little manual handling.

2. THE APPARATUS

Preferably, the apparatus 38, shown in FIGS. 1 - 31, is used for practicing the above described process. Referring to FIGS. 1 and 1a, in particular, the skid loading station 40, the first adhesive applying station 42, and the mechanical fastening station 44 are shown, with a portion of the second adhesive applying station 46 also being shown. FIGS. 2 and 2a, show the second adhesive applying station 46 and the pressure applying station 48.

As indicated previously, the apparatus 38 generally includes the skid loading station, generally 40, the first adhesive applying station, generally 42, the mechanical fastening station, generally 44, the second adhesive applying station, generally 46, and the pressure applying station, generally 48. A frame, generally 50, supports all of the operating parts of the apparatus 38. The frame 50 constitutes an important part of the invention because of its great versatility in usefulness with a variety of container sizes. The apparatus 38 is constructed and arranged to assemble the container 40, from first and second container sections 12 and 14 of widely varying widths and lengths. Also, if desired, the apparatus 38 may be operated so as to vary the number of skids 36 which are secured to container 10. As will be described hereinafter, the frame 50 and the various operating stations of the apparatus 38 may be adjusted, as longitudinally and transversely, to accommodate varying sizes of container sections.

Referring to FIGS. 1, 1a, 2, 2a and 5, the frame 50 includes an elongated lower frame section, generally 52, a mechanical fastening section support frame, generally 58, positioned intermediate the opposite ends of the lower frame 52, an overhead frame generally 60, and a rear frame section, generally 62, for supporting the pressure applying section 48 of the apparatus 38.

The lower frame sections 52 includes a pair of spaced elongated horizontal channel members 64 which are rigidly interconnected at their opposite ends by transverse end channels 66. A plurality of transverse members 68 are secured to the frame section 52, one being secured to the forward channel 66 and the other being spaced along the front of the side channels 64. The transverse members 68 project laterally beyond the side members 64. A plurality of upright supports 70 support the lower section 52 in a substantially horizontal, fixed position.

The mechanical fastening section support frame is movable longitudinally of the lower frame 52. Referring to FIGS. 2 and 6, the mechanical fastening section frame includes a pair of upright supports, generally 72, which are interconnected by a cross frame 74, which, in turn, is rigidly interconnected to the upper ends of the upright supports 72. The lower ends of the upright supports 72 are rigidly interconnected to a lower longitudinal support 76 at the central portion thereof. Each longitudinal support 76 rotatably carries a pair of spaced wheels 78 at the outer ends thereof, the wheels rollably engaging a pair of transversely spaced tracks 80. The tracks 80 are parallel to the longitudinal axis of the apparatus 38 and frame 50. By this structure the overhead frame 60 is movable to a desired position relative to the forward end of the apparatus 38 in order to accomodate skids 36 of varying lengths and first container sections 12 of varying sizes.

As will be described hereinafter, each mechanical fastener assembly, generally 82, supported by the mechanical fastening support frame 58, may be adjusted transversely so as to be adjusted to a desired positive relative to the skids 36 and to the first container section 12. Referring to FIGS. 29, 30 and 31, the lower frame section 52 is adjustable relative to the longitudinal axis of the apparatus 38, so that the relative position between the skids 36 and fastening assemblies 82 may be changed. In this regard, the side channels 64 are adjustably secured by clamps 84 to a transverse member 86. The transverse member 86 is adjustably secured to the upper end or the upright support 70 by a clamp 88 in order that the support channels which support the first container section 12, as seen in FIG. 29, may be adjusted inwardly and outwardly relative to the longitudinal axis of the apparatus 38. Overhead transverse support channels 90 mechanically support the first container section 12 in position above the skids 36 as the skids 36 are transferred to the mechanical fastening station 44.

The rear frame section 62, as seen best in FIGS. 1, 1a, 2 and 2a, includes a raised section 92, and a bottom section 94. The raised section 92 includes end and intermediate upright support columns 96 which generally define the lateral extremities of the apparatus 38, as seen best in FIG. 5. The intermediate pair and rear pair of support columns 96 are each rigidly interconnected at their upper ends by a pair of transverse or cross support beams 98, as seen best in FIG. 5. Also, each rear column 96 and each intermediate column 96 are held

rigid by longitudinal beams 99 secured to the outer upper surfaces of the cross beams 98. Longitudinal support beams 100 rigidly interconnect the upper ends of each front column 96 and each intermediate support column 96, as seen best in FIGS. 2 and 2a.

The bottom or lower section 94 of the rear frame section 62, as seem best in FIGS. 1a, 2a and 5 includes a pair of lateral support frames 102, which support the lateral edges of the second container section 14 as seen best in FIG. 5. The lateral frames 102 each include upright supports 104 and transverse supports 105 which are rigidly interconnected to the upright supports 104. A rigid longitudinal side guide member 108 is secured to the upper surface of the frame 102 and is laterally adjustable thereon in order to guide the lateral edges of the second container section 14 into proper position at the pressure applying station 48, regardless of the particular width of the container section being guided thereon.

The skid loading station 40 is seen best in FIG. 1, 2, 13, 14 and 15. Referring to FIGS. 1 and 2, the skid loading station 40 includes a plurality of spaced, longitudinal skid supports, generally 110, and a conveyor mechanism, generally 112.

Each skid support 110, as seen best in FIG. 15, includes a pair of longitudinal angle members 114 and 116, which cooperate with each other to define an upwardly opening skid receiving channel 118. An upright support column 120 is rigidly secured to the underside of the channel defining members 114 and 116 to vertically support the outermost end of the skid support assembly 110. The angle member 114 of each pair of angle members 114 and 116 is laterally adjustable relative to the angle member 116 so as to accomodate skids 36 of varying widths. A plate 122 is secured to the underside of the angle member 116 and a clamp member 124 is secured to the transverse plate 122 so as to adjustably position the angle member 114 relative to the angle member 116 for accomodating skids 36 of various widths. The rear portions of the angle members 114 and 116 are rigidly secured to the lower frame section 52 as best seen in FIGS. 1 and 2.

The conveyor mechanism 112 includes an air drive cylinder 126 which is rigidly secured at its inner or rear end to an angle support 128 which is rigidly mounted on one of the channel defining angle members 114 and 116, as seen in FIG. 1. The longitudinally elongated air drive cylinder 126 in its fully extended position, is as long as the angle members 114 and 116 of the skid support assembly 110. A piston rod 130 projects frontwardly from the air drive cylinder 126 and is rigidly secured at its outermost end to a pusher plate 132, as seen in FIG. 15. The pusher plate 132 comprises an upright plate positioned within the channel 118 for moving a skid 36 forwardly past the adhesive applying station 42 to the mechanical fastening station 44.

As seen in FIGS. 13, and 15, the pusher plate 132 is interconnected to the piston rod 130 by a connecting member 134. The connecting member 134 includes an upright plate portion 136 and a transverse, horizontal plate portion 138, which is integral with the upright plate 136. The upright plate 136 is fixedly secured to the outer end of the connecting rod 136 by a nut 140, which is threadably secured to the threaded outer end of the rod 130. As seen in FIG. 15, the transverse horizontal plate 138 is rigidly secured, as by welding, along one edge to the upright pusher plate 132. The move-

ment of the piston rod 130 of the air cylinder 126 imparts reciprocal movements to the pusher plate 132 on the skid support 110 for first moving the skids along a desired path of travel and the the mechanical fastening station 44. In order to properly guide the movement of the pusher plate 136, a conveyor guide assembly, generally 142, is provided.

The conveyor guide assembly 142 includes an overhead support plate 144 which is secured at its outer end to a support member 146, which, in turn, is rigidly secured to the front or outer end of the skid support 110 and specifically to the front or outer ends of the angle members 114 and 116, as seen in FIGS. 13 and 14. The support plate 144 extends for the entire length of the skid support 110 and is positioned generally above the air cylinder 126. The inner or rear end of the support plate 144 is secured to the same angle support 128 to which the air cylinder 126 is connected, as best seen in FIG. 1.

As seen in FIG. 15, the underside of the longitudinally elongated horizontal support plate 144 has an angle member 148 fixedly secured to the underside thereof. The upright portion of the angle member 148 is spaced from and aligned directly above the upright portion of the angle member 116 for defining an elongated, horizontal slot 150 therebetween. The width of the slot is such as to permit the passage therethrough of a horizontal or transverse portion 138 of the connecting member 134 so that the vertical position of the pusher plate 132 is properly guided in the vertical direction.

Four sets of rollers 152 are rotatably carried by the transverse plate 138 of the connecting member 134. The rollers 152 are carried on upright axes 154 with the roller guide 152 on each axis 154 being positioned on opposite sides of the transverse plate 138. As seen in FIG. 13, the outer periphery of each of the rollers 152 is spaced opposite another cooperating roller on opposite sides of the upright portions of the angle members 114 and 148 for providing smooth movement for the pusher plate 132 as it tranfers a skid 36 to the mechanical fastening station. A support block 156 is rigidly secured to the underside of the central portion of the transverse plate 138 and a threaded shaft 158 is threadably received therein. The shaft 158 is horizontally and transversely positioned relative to the longitudinal axis of the machine axis. A roller 160 is carried on the shaft 158 and the outer periphery thereof rides on or bears against the upper surface of the horizontal portion of the angle member 114 for vertically supporting the pusher plate assembly 132 during movement thereof.

The adhesive applying station 42 is seen best in FIGS. 1, 2, 16 and 17. The adhesive applying station 42 includes a support, generally 162, a glue attachment, generally 164, a start limit switch, generally 166, and a stop limit switch, generally 168. The support 162, as seen in FIG. 16, generally includes an upright plate 170 having flanges 172 thereon. The flanges 172 include lower lips 174 which are secured, as by welding, to the upper surface of the horizontal, elongated support plate 144 of the skid support assembly 110.

The glue attachment 164 includes a transverse shaft 176 which is fixedly mounted on the support plate 170 as seen in FIG. 17, and which projects laterally therefrom and is positioned generally above the skid channel 118. A support arm 178 is rotatably carried on the shaft 176 and projects forwardly and slightly downwardly

therefrom, as seen in FIG. 16. A coil spring 180 is mounted on the shaft 176 and acts to normally bias the arm 178 in a downward direction and towards a skid 36 being moved along the skid channel 118. A glue gun 180, of conventional design, is mounted on the arm 178 with a glue applicator 184 being located at the lower surface thereof. As conventional openings are provided therein for dispensing glue therethrough, the adhesive or glue passes through a hose or line 186 which is interconnected to a pressurized glue source (not shown). The spring 180 normally maintains the applicator 184 in engagement with the upper surface of the skid 36 so as to assure continuous application of the glue or adhesive to the upper surface of the skid.

15 The start switch 166 includes a switch block 188 which is fixedly mounted to one face of the support plate 170 and a switch arm 190, normally biased in a downward direction is mounted thereon. The switch arm 190 is movable between a downward pivoted position below the upper surface of a skid 36 and an upward position, as seen in FIG. 16, when the limit switch arm 190 is in contact with the upper surface of the skid 36. As the leading edge of the skid 36 engages the downwardly biased arm 190 of the start switch 166, the switch is actuated and pressure is applied to the glue source so that glue is applied to the upper surface of the skid through the applicator 184.

20 The stop switch 168 is generally of the same construction as the start switch 166 and includes the support block 188 and arm 190. In both cases, the roller portion or lower end of the arm 190 is movable or pivotable in and out of engagement with only the upper surface of the skid 36. In the case of the stop switch 168, it is particularly important to avoid contact with the glue. For this reason the roller 192 is offset from the glued section. When the trailing edge of the skid 36 passes the stop limit switch 168, the application of adhesive or glue to the skid is stopped. A glue attachment 164 is provided for applying adhesive or glue to the 25 upper surface of each skid 36, as seen in FIG. 1. Glue is continuously applied from the attachment 164 as the skid 36 passes thereby.

30 The skids 36 continue their movement along the desired path of travel, past the first adhesive applying station 42, by action of the conveyor mechanisms 112. This movement continues until the mechanical fastening station 44 is reached. At this time, each of the skids 36 remains stationary for a brief period of time.

35 As seen in the schematic drawings of FIGS. 34 and 35, the first container section 12 is positioned directly on top of the skids 36 with the lateral edges of the bottom surface of the bottom wall 16 being aligned with the lateral edges of the two end skids 36 while the rear edge of the bottom wall 16 is aligned with the trailing ends of the skids 36. The first container section 12 may be manually positioned on the skids 36, although suitable equipment could feed the first container section 12 into the desired position for stapling or mechanical fastening. The mechanical fastening station 44 is best seen by referring to FIGS. 1 - 4 and 6-12.

40 As described earlier, one mechanical fastener assembly 82 is provided for driving staples or the like through the first container section 12 and into each one of the leading edges of the skids 36. This portion of the apparatus and process is an important feature of the invention. While the skids 36 are stationary, with the first section 12 thereon, one staple only is driven through

aligned portions of the first container section 12 and into each of the skids 36. As explained previously, when this is accomplished, all three skids and the container section 12 may be moved simultaneously for the second gluing operation and, at the same time, multiple aligned mechanical fasteners, as staples, are driven consecutively through the first container section and into each of the skids 36.

In order to assure proper positioning and alignment between each of the skids 36, as the conveyor mechanism 112 carries the skids 36 to the mechanical fastener station 44, the leading edges of the skids 36 are stopped in their forward movement at a predetermined position by a plurality of stop mechanisms, generally 194, as seen best in FIGS. 1, 9 and 12.

Each stop mechanism 194 is fixedly but adjustably and removably secured to a transverse support 196 on the mechanical fastener frame 58, as seen in FIGS. 1 and 9. The support 196 is secured at its opposite ends to a pair of support plates 198 which are secured, in turn, to the spaced upright supports 72 of the mechanical fastener support frame 58. The horizontal cross support 196 is located slightly downstream of the mechanical fasteners 82. Each stop mechanism 194 includes a support portion, generally 200, an air drive cylinder 202, and a movable stop portion 204. The support portion 200 comprises an upright plate 206 with a connecting section 208 which is secured to the cross support 196 by a pair of adjustable bolts 210.

The air cylinder 202 is pivotally secured at 212 to an arm 214 projecting from the upright plate 206. The piston rod 216 of the air cylinder 202 is pivoted at 218 to a pair of links 220. The links 220, in turn, are secured at a pivot 222 to the support portion 200. The upper portion of the stop 204 is pivoted at 224 to the support portion 200. A link 226 is positioned intermediate the links 220 and is pivotally secured at its opposite ends to the pivot 218 on the rod 216 and to a pivot 228 on the stop 204 just below the pivot connection 224.

As illustrated in FIG. 9, the air cylinder 202 adjusts the stop 204 to the downwardly lowered vertical position to stop the forward movement of the skids 36 and laterally align them below the mechanical fastener assemblies 82. As will be described, after one staple has been inserted through the first container section 12 and into each of the skids 36, the air cylinder 202 is activated to pivot the stop 204 upwardly to the horizontal position shown in dotted lines in FIG. 9, so that the skids 36 and the first container section 12 may be moved in the desired path of travel for completing the mechanical fastening operation and for thereafter moving the assembled skids and first container section past the second adhesive applying station 46.

A vertically movable, generally horizontal transverse support 230 carried each of the mechanical fastener assemblies 82. An upright brace 232 is positioned on the opposite ends of the cross support 230 and, as seen best in FIGS. 6 and 8, each upright brace rotatably carries a pair of grooved guide wheels 234. The guide wheels 234 ride on upright tracks fixedly secured to the spaced upright supports 72 of the mechanical fastener support frame 58. The cross support 230 is vertically movable and vertical motion is imparted to the cross support 230 and thereby to each of the mechanical fastener assemblies 82 by a drive cylinder 238.

As seen in FIGS. 6 and 9, the drive cylinder 238 is mounted in a substantially vertical position on the

upper surface of the cross brace 74 of the mechanical fastener support frame 58. The piston rod 240 is pivotally secured at 242 to the central portion of the cross support 230. The drive cylinder 238 imparts reciprocal movement to the cross support 230 and thereby to the fasteners 82 with the opposite ends of the cross support 230 guiding the vertical reciprocal movement by cooperation between the guide wheels 234 and tracks 236.

Each mechanical fastener assembly 82 includes a support portion, generally 244, and a nailing or stapling gun 246. As seen best in FIGS. 9, 10 and 11, the support 244 includes an upper plate 248 having a pair of connecting flanges 250 which are positioned above the flange of the cross support 230. Bolts 252 removably and adjustably secure the fastener support 244 to the cross support 230. A pair of plates 254 extend vertically downwardly from the upper plate 248 and a lower horizontal plate 256 rigidly interconnects the ends of the plates 254. Another upright plate 258 projects downwardly from the lower plate 256. The upright plate 258 has a plurality of roller guides 260 mounted thereon.

The support 244 includes a movable portion 262 which rigidly supports the stapling or nailing gun 246. A horizontal plate 264 is positioned intermediate the lower plate 256 and plate 248 and is vertically movable between the plates 254. The guide rollers 260 rollably engage the upright edges of upright, spaced support bars 266, which are secured to the outer edges of the horizontal plate 264 so as to provide relative movement between the movable support 262 and the support plate 248 which is rigidly carried by the cross support 230.

A horizontal bar 268 interconnects intermediate portions of the forward portion of support bars 266 and the rear, shortened, upright support bar 270. The lower ends of each of the support bar 266 and the shortened bar 270 rotatably carries roller members 272 which, as seen in FIG. 9, are constructed and arranged to bear against the upper surface of the first container section 12 and are rollably engaged therewith during movement of the skids 36 and the first container section 12 past the stapling guns 246. The relative vertical movement provided between the movable support 262 and support plate 248 assures that the stapling or nailing gun 246 will be properly positioned against the upper surface of the first container section 12 regardless of variations in thickness of skids 36 being moved thereby. The gun 246 is rigidly secured to the support bars 266 and 270, which define a support cage therearound. The gun 246 is a conventional type of stapling or automatic nailing gun which is adapted to rapidly fire mechanical fasteners, such as staples or nails through the first container section 12 and into the skids 36. A cross brace 274 (FIG. 7) interconnects each of the spaced pairs of support bars 266 so as to provide exceptionally rigid support for the gun 246.

As seen in FIGS. 6 and 7, a limit switch 276 is secured to the cross support 230 by means of a support bracket 278. When the drive cylinder 238 has lowered the mechanical fastener assemblies 82 into position against the upper surface of the first container section so that the nails or staples may be driven thereinto, the limit switch 276 indicates this position has been reached so as to activate the gun mechanism 246 to drive one staple only through the first container section 12 and into each of the skids 36. After the first staple

is driven the partially assembled container parts are then moved simultaneously and continuously past the mechanical fastening station 44 for having a plurality of nails or staples driven into the first container section and into each of the skids 36.

A chain conveyor, generally 280, as seen best in FIGS. 1, 1a, 2, 2a, 5 and 20-26, is used to move the partially assembled container from the brief stop position at the mechanical fastening station to the pressure applying station while moving the container, in its partially assembled condition, past the second adhesive applying station and past the mechanical fastening station. The chain conveyor 280 is connected to the lower frame section 52. As seen in FIGS. 1a and 2a, a transverse drive shaft 282 is rotatably carried in suitable bearings in the frame section 52. The opposite end of the chain conveyor 280 includes an idler shaft 284 which is also suitably rotatably carried in the lower frame section 52. The conveyor 280 includes two substantially identical, but spaced conveyor sections 286. Each conveyor section 286 generally comprises a pair of spaced chains 288 having a plurality of pushed members 286 operatively supported by and between spaced chains 288 of the chain conveyor assembly 280.

The chain conveyor 280 includes a drive mechanism, generally 292 for operating the chain conveyor 280. The drive mechanism 292, as seen best in FIGS. 1a and 2a, generally includes a motor-gear reducer set 294. A transverse drive shaft 296 projects from the gear set 294 and a drive sprocket 298 is non-rotatably mounted thereon. The drive sprocket 298, in turn, operatively engages a drive chain 300. The drive chain 300 drivably engages a sprocket 302 of a torque limiter which is normally non-rotatably mounted on the conveyor drive shaft 282. In this way, the drive shaft 282 is rotated, in a clockwise direction as viewed in FIG. 2a, for moving the conveyor chains 288 in a forward direction, thereby moving the partially assembled first container section 12 and skids 36 past the mechanical fastening station 34, past the second adhesive applying station 46, and to the pressure applying station 48.

A pair of spaced sprockets 304 are non-rotatably mounted on the drive shaft 282 for each conveyor section 286. The sprockets 304, in turn, operatively engage the chains 288. The front ends of the chains 288, as seen in FIG. 1, engage the sprockets 306, which are mounted on the idler shaft 284.

As seen in FIGS. 23 and 24, a spacer hub 308 is positioned on the drive shaft 282 for separating the hubs of the sprockets 304 the desired amount. As seen in FIGS. 25 and 26, an adjustable clamp 310 is mounted on the drive shaft 282 for adjustably positioning the sprockets 304 and 308 thereon.

Referring to FIGS. 20-22, a hub 312 is mounted between the sprockets 306 on the idler shaft 284. A clamp 314 adjustably positions the sprockets 306 and hub 312 at the desired position on the idler shaft 284. A radially projecting cam plate 316 projects from the outer periphery of the hub 312. A plurality of the spaced pusher members 290, as seen in FIGS. 20-25, are each rotatably carried on one of a plurality of shafts 318 which extend between the spaced chains 288. The opposite ends of the shaft 318 are fixedly received within mounting supports 320 which are, in turn, fixedly secured to the inner faces of the opposed links on the spaced drive chains 288. Each pusher 290 generally includes a normally upright pusher portion 322

and longitudinally projecting side plates 324. The side plates 324 are interconnected at their trailing ends to a shaft 326. The shaft 326 rotatably carries a cam roller follower 328. A lower plate 330 is positioned between the side plates 324 and the upright plate 322.

An elongated longitudinal, substantially horizontal straight cam 332 intercepts the upper outer periphery of the cam plate 316 at the front portion of the conveyor chain 280 and extends rearwardly to the opposite end of the chain conveyor 280, as seen best in FIG. 23. As seen in FIG. 20, as the pusher members 290 approach the area of the idler shaft 284, the lower plate 330 thereof engages the outer periphery of the cam plate 316 in the manner illustrated in FIG. 20, and the pusher plate moves into the upright position as seen in FIG. 20. In this position, the upright plate of the pusher 290 engages the trailing edges of the first container section 12 and moves the assembled skids 36 and first container section 12 past the mechanical fastening station 44 and past the second adhesive applying station 46. Since two pairs of chain conveyors 280 are generally used, the pusher plate assemblies 290 on each of the conveyor chain sets 280 are laterally aligned with each other, so as to move the assembled skids 36 and first container section 12 in a path of travel so that the longitudinal axis thereof is in substantial alignment with the longitudinal axis of the apparatus 38 for movement thereof in the desired path of travel.

As seen in FIG. 23, when the pusher reaches the drive shaft area, the cam plate 332 terminates and the pusher plate pivots downwardly, by action of gravity, to the dotted line position, shown in FIG. 23. At this time, as will be explained hereinafter, the assembled first section 12 and skids 36 are then positioned to have the second container section 14 secured to the first container section 12 and thereby completing the assembly of the container 10. As seen in FIGS. 23 and 24, a substantially horizontal guide plate 334 guides the container section 12 to the pressure applying section 48.

Referring to FIGS. 1, 3 and 4, one end of the idler shaft 284 is non-rotatably interconnected to a plate 336 which has a plurality of circularly spaced pins removably mounted near the outer periphery thereof. A switch 340 is mounted on the frame, and includes a biased arm 342 having a roller 344 thereon. The roller 344 is designed to engage the pins 338 on the idler shaft 284 as the shaft 284 rotates while the chain conveyor 280 moves the partially assembled first container section 12 and skids 36 along the preselected path of travel. Each time a pin 338 rotates the arm 342, the stapling gun 246 is actuated to drive one staple or nail into the first container section 12 and through each of the skids 36. A plurality of such staples are thereby driven in accordance with the number of activating pins 338 mounted on the plate 336. Since the pins 338 are removable, the spacing of the staples or nails and the number per unit length of stapled area are readily controlled.

Referring to FIGS. 1a, 2a, 18 and 19, the second adhesive applying station includes a pair of laterally spaced glue applying assemblies 346 which are mounted on the lower frame section 52 and apply adhesive or glue to the flaps 20 of the first container section 12 so that the second container section 14 may be secured to the first container section 12 at the pressure applying station 48. As seen best in FIG. 1a, each glue applying assembly 346 is spaced apart a distance corre-

sponding to the location of the upper surface of each flap 20 of the first container section 12.

Referring particularly to FIGS. 18 and 19, each glue assembly 346 includes a flap hold down assembly, generally 348, a start glue switch 350, a stop glue switch 352, and a glue mechanism, generally 354. The flap hold down 348 generally includes an upright support arm 356 which is secured to the lower frame section 52. The upper end of the arm 356 carries a vertically adjustable transverse rod 358 which has a flap hold down spring 360 thereon. The spring 360 is designed to bear against the upper surface of the flap upstream of the glue mechanism 354 so that the flap is properly held in a substantially horizontal position as the glue is being applied thereto by the glue mechanism 354. The rod 358 is vertically adjustable with a slot 362 in the arm 356. The glue mechanism 354 includes an upright support arm 364, which is rigidly secured to the frame 52 and is aligned with and spaced down stream of the support arm 356. A transverse support shaft 366 is mounted within a vertically elongated slot 368 and is held in place by nuts 370 positioned on opposite sides of the arm 354. The shaft 366 rotatably carries a support 372 which is normally biased in a downward direction by a biasing spring 374. A glue attachment 376 is mounted on the support 372 and terminates in a glue head 378 having apertures therein through which glue or adhesive passes. The head 378 communicates with a glue supply line 380 which communicates with a glue source (not shown).

The glue start switch 360 includes a switch portion 382 which is fixedly secured to the frame 52. A biased arm 384 projects therefrom and is movable into engagement with the undersurface of the first container section 12. When the leading edge of the first container section 12 is being moved by the chain conveyor 280, and the leading edge of the container section 12 moves the arm 384 downwardly, a signal is generated, and ultimately causes the glue attachment 376 to commence applying glue to the flaps of the first container section 12.

The stop glue switch 352 includes a switch body 382 and a biased arm 384. When the trailing edge of the first container section 12 has passed the switch 352, a signal is generated which stops glue from being applied through the glue attachment 376.

As the first container section 12 is being conveyed to the pressure applying station 48, the second container section 14, as shown schematically in FIG. 36, is manually positioned on a longitudinally adjustable support frame 386 which is mounted on the overhead frame 60. The support frame 386 includes a pair of spaced upright supports 388 which include a pair of forwardly projecting supports or angle members 390. The upper ends of the upright supports 388 are vertically and adjustably interconnected to a carriage 392. The carriage 392 includes an upright interconnecting portion 394 and a wheel support portion 396. The interconnecting portion 394 is connected to the upright portion 388. The wheel support 396 rotatably carries a pair of wheels 398 which are movable along the longitudinal beams of the overhead frame 60.

As seen in FIG. 1a, a plurality of transversally elongated roller supports 400 are fixedly secured at their opposite ends to the longitudinal supports 390 of the support frame 386. The roller supports 400 provide a convenient storage position for the second container

section 14 before the second container section 14 is aligned directly on top of the first container section 12 for securement thereto along the glued flaps 14 of the first container section 12.

The chain conveyor 280 moves the first container section 12 to the pressure applying station 48 for the completion of the processing and assembling of the container 10. The pressure applying station 48 is shown most clearly in FIGS. 1a, 2a, 5, 27 and 28. The pressure applying station 48 includes a plurality of roller conveyors, generally 402, which are positioned just downstream of the rear end of the chain conveyor 280, and which rollably convey and receive the first container section 12. The pressure applying station 48 also includes a pair of spaced overhead, elongated pressure applying ram assemblies, generally 404. The pressure applying station further includes a pair of stop assemblies, generally 406.

As the chain conveyor 280 carries the first container section into the pressure applying station, the leading edge of the first container section 12 strikes a switch arm 407 which is pivotally carried on the limit switch 409. The switch 409 when actuated, causes the stop assemblies 406 to be activated and move from the upright stop position, shown in solid line in FIG. 27, to the dotted line, lowered position of FIG. 27. When the leading edge of the container section 12 strikes the arm 411 of the limit switch 413, the rams 48 are raised. With the stops 406 lowered and rams raised, the previous assembled container 10 can be removed to make room for the next container to be assembled. The leading edge of the container section 12 then strikes the arm 415 of the limit switch 417 to again activate the stops 406 and raise them to the upright stop position. As seen in FIG. 1a, five conveyor assemblies 402 are transversely spaced from each other and are parallel with the central axis of the apparatus 38. Desirably, a plurality of laterally aligned stop assemblies 406 are positioned near the rear or trailing ends of the roller conveyor assemblies 402, preferably on the second and fourth conveyor assemblies 402, illustrated in FIG. 1a.

Referring to FIGS. 27 and 28, each stop assembly 406 includes a mounting bracket 412 which is adjustably secured to the roller conveyor assemblies 402 by clamps 414. Specifically, the longitudinal position of the assemblies 406 is readily adjusted by sliding the clamps 414 relative to the roller conveyor assembly 402. A cylinder support bracket 416 is mounted in a substantially horizontal position and is secured to the bracket 412. A downwardly projecting leg 418 is provided on the bracket 416. An air drive cylinder 420 is pivotally secured to the leg 418. A piston rod 422 projects rearwardly from the cylinder 420 and is pivotally interconnected at 424 to a pair of spaced, L-shaped links 426.

Each stop assembly 406 also includes a pivotable stop plate 428 which is pivotally secured at 430 to the air cylinder support bracket 420. The L-links 426 include an intermediate pivot 432 which pivotally secures the links 426 to the cylinder support bracket 416. The L-links 426 also include an outer pivot point 436, with a shaft 438 pivotally carrying a link 440 which, in turn, is pivotally secured to the stop plate 428 at a pivot point 442. As air pressure is applied to the opposite ends of the air drive cylinder 420, the stop plate 428 is pivoted from the retracted or horizontal position, shown in dotted line in FIG. 27, to the raised or stop

position shown is solid line view in FIG. 27. When the limit switch 410 is activated by the leading edge of the first container section 12, the air drive cylinder 420 is activated to move the plate 428 to the position for stopping and engaging the leading edge of the first container section 12 as the chain conveyor 280 moves the container section 12 with the skids 36 secured thereon to the stop position in the pressure applying station 48.

The roller conveyors 402 generally comprise horizontally and longitudinally spaced roller support channels 444. The outer pair of roller conveyors 402 are supported on the frames 62. The second and fourth roller conveyors 402 are generally aligned with the chain conveyors 280 and the middle roller conveyor 402 is generally aligned with the central axis of the apparatus 38. The supports 444 of the three intermediate roller conveyors 402 include vertically adjustable upright rear supports 446. The channels 444 rotatably carry a plurality of rotatable rollers 448 for rollably receiving and conveying the first container section 12 to the raised stop plates 428 from the motion imparted thereto by the chain conveyor assembly 280.

As seen best in FIGS. 2a and 5, the overhead ram assembly 404 includes a support section 450 and a ram section 452. The overhead ram assembly 404 comprises two similarly constructed portions, each having a support section 450 and a ram section 452.

The support section 450 includes a pair of end sections 454 and as seen best in FIG. 2a, a longitudinal cross beams 456, which interconnect the lower ends of the end sections 454. Each end section 454 includes a pair of relatively closely spaced upright channels 458, each being secured to the lower ends of the cross beam 456. The upper ends of the upright channels 458 are interconnected by a roller support assembly 460.

The roller support assembly 460 includes a pair of longitudinally spaced horizontal arms connected at their intermediate portion to each of the upright channels 458. Shafts 464 are secured to the opposite ends of each of the arms 462 and interconnect the arms 462. A pair of roller wheels 466 are rotatably carried on each of the shafts 464. The wheels 466 ride along the upper surface of each of the cross beams 98 of the rear frame section 62. The channels 458 are positioned on the opposite sides of the beams 98. As seen best in FIG. 5, the wheels 466 enable the spaced ram sections 452 to be properly laterally aligned above the laterally spaced, glued flaps of the first container section 12 and above the second container section 14. After the ram sections 452 have been properly aligned, a lock 458 is provided for securing each roller support assembly 460 in the desired position.

The ram section 452 includes a substantially upright hydraulic drive cylinder 470 which is secured to the cross beam 456 intermediate the opposite ends thereof. A piston rod 472 extends from the lower end of the drive cylinder 470 and is rigidly interconnected to the central portion of a horizontal pressure beam 474. The opposite ends of the pressure beam 474 are rigidly interconnected to the lower ends of a pair of upright guide rods 476. The guide rods 476 slidably engage the cross beam 456 in order to guide the reciprocal movement imparted to the pressure beam 474.

An upper limit switch 478 and a lower limit switch 480 are mounted on a support bracket 482 which is attached to the cross beam 456. Each limit switch 478 and 480 includes a switch arm 484. One of the guide

rods 476 has an upper collar 486 and a lower collar 488 mounted thereon. The collars 486 and 488 are vertically adjustable so as to properly position the pressure beam for applying pressure against the second container section 14, in the area where glue has been applied to the flap 20 on the first container section 12. In order to lower the beam 474 when the two container sections 12 and 14 are properly positioned, a pair of palm switches (not shown) are pressed to activate the cylinder 470. When the upper collar 486 strikes the arm 484 of the upper switch 478, the switch 478 generates a signal to stop the downward movement of the drive cylinder 470 in order to compress the second container section against the flaps 20, with a frame of about 2000 pounds and a pressure of about 10 psi, for providing time for the adhesive to set and provide securement therebetween. As indicated previously, when the switch 413 is activated, each drive cylinder 470 raises the pressure beams 474 upwardly. When the lower collar 488 contacts the lower switch arm 484, pressure to the drive cylinder 470 is stopped and the beam 474 is stopped in the raised position.

After the first container section 12 has been moved into position against the stop plates 428, the second container section 14 is removed from the support frame 386 and aligned in such a way that the glued flaps 20 are positioned against the desired section of the second container section 14 so that the beam 474 holds the desired sections of the two container sections 12 and 14 in compressing relationship so that the glue sets to permanently secure the two container sections together. The rapid setting of the glue or adhesive is a relatively short period of time, as about ten seconds, is accomplished by the pressure from the beams 474. Despite the large size of the container sections, the adhesive binds the two container sections 12 and 14 together with sufficient strength to enable simultaneous movement therebetween.

As indicated previously, when the desired amount of time has elapsed, the pressure beams 474 are raised upwardly and the completely assembled container 10 is removed from the apparatus in the flattened or collapsed condition. The container 10 can then be opened in the manner illustrated in FIGS. 41 and 42.

It is seen from the foregoing, that the apparatus 38 readily assembles the container 10 in a highly convenient and simple manner. The apparatus 38 conveys a plurality of skids 36 by the conveyor mechanism 112 past the glue attachment 164 where the glue is applied to the upper surface of the skids. The skids 36 are then moved against the stop mechanism 194 for a very brief period of time sufficient for the first container section to be positioned on top of the skids 36. The stapling and nailing guns 246 are activated one time for driving one staple or nail through the first container section 12 and into each of the skids. As soon as this is accomplished, the chain conveyor 280 is activated for moving the partially assembled skids 36 and container section 12 past the nailing guns 246 to have multiple staples or nails applied into each of the skids 36. During the same movement by the conveyor 280, the second glue assemblies 346 apply glue to the flaps 20 of the first container section 12. The conveyor 280 carries the first container section 12 onto the pressure applying station 48 until they are moved against the stop assemblies 406. The second container section 14 is then positioned on top of the first container section 12 in such

a way that the portion thereof which is to be glued to the first container section is aligned with a glued flap. Thereafter, the hydraulic cylinder 470 is activated to drive the pressure beam 474 of each ram section 452 downwardly to compress the glued flaps and second container section between the frame and the beam 474 for a sufficient period of time to permit the adhesive to set and permanently secure the two sections together. After the ram 474 is raised, the assembled container may be removed and then later opened for receiving articles to be shipped.

While in the foregoing, there has been provided a detailed description of a particular embodiment of the present invention, it is to be understood that all equivalents obvious to those having skill in the art are to be included within the scope of the invention as claimed.

What we claim and desire to secure by Letters Patent is:

1. Apparatus for assembling a container having first and second sections and having a plurality of rigid skids secured to the underside thereof, said apparatus comprising, in combination, a skid positioning station, a first gluing station, a mechanical fastening station, a second gluing station, a pressure applying station, means for transferring a plurality of said skids in aligned and spaced relationship from said skid positioning station, to said mechanical fastening station, means for applying adhesive to the upper surface of each of said skids during the transfer thereof to said mechanical fastening station, means for applying one mechanical fastener into each skid, and through said first container section, means for conveying said partially assembled skids and first container section simultaneously from said mechanical fastening station and past said second adhesive applying station while applying additional mechanical fasteners into each of said skid and through said first container section, means for applying adhesive at said second adhesive applying station to portions of said first container section, means for stopping and positioning said first and second container sections so that portions of said second container section overly said portions of said first container section having adhesive thereon, and means for applying mechanical pressure to said first and second container sections where said adhesive has been applied for setting said adhesive and thereby adhesively securing said first and second container sections together.

2. The apparatus of claim 1 wherein said skid positioning station includes a plurality of laterally aligned support means for said skids, and said transferring means is operatively associated with said skid support means.

3. The apparatus of claim 2 wherein said transferring means comprises an air cylinder drive means, and a pusher plate connected to said air cylinder drive means for engaging said skids and for moving said skids from said skid positioning station.

4. The apparatus of claim 1 wherein said first gluing station includes a glue applicator, means for normally biasing said glue applicator into contacting relationship with the upper surface of said skids, and switch means for starting and stopping the flow of glue through said applicator.

5. The apparatus of claim 1 including a frame for supporting said skid positioning station, said first gluing station, said mechanical fastening station, said second gluing station, and said pressure applying station, said

frame including means for adjustably mounting said stations for accommodating skids and container sections of varying sizes.

6. The apparatus of claim 1 wherein said mechanical fastening station comprises frame means, a plurality of mechanical fastening devices mounted on said frame means over said skids for applying said mechanical fasteners through said container section and into each of said skids.

7. The apparatus of claim 6 wherein said mechanical fastener device includes means for controlling the number and spacing of fasteners driven into each of said skids.

8. The apparatus of claim 1 wherein said second gluing station comprises a glue applicator means normally biased against said second container section portion, and switch means for starting and stopping the application of glue through said glue applicator means.

9. The apparatus of claim 1 wherein said pressure applying station includes an overhead frame means, and a pressure beam vertically reciprocally mounted on said frame means for movement in and out of pressure applying relationship with said overlying container sections.

10. The apparatus of claim 1 wherein said conveying means comprises a pair of chain conveyors including means secured thereto for engaging said first container section and for conveying said first container section and said skids from said mechanical fastening station to said pressure applying station.

11. Apparatus for assembling a container having first and second sections, said first section having a bottom wall and a first side wall with flaps, said second section having a second side wall and lateral end walls, and a plurality of rigid skids secured to the underside of said bottom, said apparatus comprising, in combination, a skid positioning station, a first gluing station, a mechanical fastening station, a second gluing station, and a pressure applying station, means for transferring a plurality of said skids in aligned and spaced relationship from said skid positioning station to said mechanical fastening station, said first gluing station including means for applying adhesive to the upper surface of each of said skids during the transfer thereof to said mechanical fastening station, means for applying one mechanical fastener into each skid and through said first container section, means for conveying said partially mechanically fastened skids and said first container section simultaneously past said second adhesive applying station and to said pressure applying station, said second gluing station including means for applying adhesive to the upper surface of said flaps, means for stopping and positioning said first and second container sections so that portions of said second section overly said flaps with adhesive thereon, and said pressure applying station includes means for applying mechanical pressure to said flaps with adhesive thereon and overlying portions of said second section for setting said adhesive and adhesively securing said first and second container sections together.

12. The apparatus of claim 11 wherein said skid positioning section includes a plurality of laterally aligned support means for said skids, and said transferring means is operatively associated with said skid support means.

13. The apparatus of claim 12 wherein said transferring means comprises an air cylinder drive means, a

pusher plate connected to said air cylinder drive means for engaging said skids and moving said skids from said skid positioning station.

14. The apparatus of claim 11 wherein said first gluing station includes a glue applicator, means for normally biasing said glue applicator into contacting relationship with the upper surface of said skids, and switch means for starting and stopping the flow of glue through said applicator.

15. The apparatus of claim 11 including a frame for supporting said skid positioning station, said first gluing station, said mechanical fastening station, said second gluing station, and said pressure applying station, said frame including means for adjustably mounting each of said stations for accommodating skids and container sections of varying sizes.

16. The apparatus of claim 11 wherein said mechanical fastening station comprises frame means, a plurality of mechanical fastening devices, mounted on said frame means over said skids for applying said mechanical fasteners through said container section and into each of said skids.

17. The apparatus of claim 16 wherein said mechanical fastener device includes means for controlling the number and spacing of fasteners driven into each of said skids.

18. The apparatus of claim 11 wherein said gluing station comprises a glue applicator means normally biased against said second container section portion, and switch means for starting and stopping the application of glue through said glue applicator means.

19. The apparatus of claim 11 wherein said pressure applying station includes an overhead frame means, and a pressure beam vertically reciprocally mounted on said frame means for movement in and out of pressure applying relationship with said overlying container sections.

20. The apparatus of claim 11 wherein said conveying means comprises a pair of chain conveyors including means secured thereto for engaging said first container section and for conveying said first container section and said skids from said mechanical fastening station to said pressure applying station.

21. Apparatus for assembling a container having first and second sections said first section having a bottom and side flaps, and a plurality of rigid skids on the underside of said bottom, said apparatus comprising, in combination, means for applying adhesive to the upper surface of each of said skids, means for thereafter mechanically securing said bottom of said first section to the upper surfaces of said skids with said adhesive thereon, means for applying adhesive to the upper surface of each of said flaps of said first section, means for stopping and positioning said first and second container sections so portions of said second section overlie said flaps with adhesive thereon, and means for applying mechanical pressure to said flaps and overlying portions of said second section until the adhesive thereon has set for securing said first and second container sections together.

22. The apparatus of claim 21 wherein said adhesive applying means includes switch means for starting and stopping the application of adhesive to said skids and said flaps.

23. The apparatus of claim 22 wherein said mechanical securing means includes control means for applying one mechanical fastener only through said first con-

tainer section and into each of said skids while said first container section and said skids are in a fixed position and means thereafter convey said partially assembled skids and first container section while multiple mechanical fasteners are inserted through the first container section and into each of said skids.

24. The apparatus of claim 21 including first conveyor means for carrying said skids past said skid adhesive applying means and to said mechanical securing means, and second conveyor means are provided for transferring said partially assembled first container section and said skids from said mechanical securing means past said flap adhesive applying means and to said mechanical pressure applying means.

25. In apparatus for assembling a container to a plurality of rigid members, said apparatus comprising, in combination, means for applying adhesive to said rigid members, means for moving said rigid members along a path of travel relative to said adhesive applying means while said adhesive applying means applies adhesive to said rigid members, means for applying a single mechanical fastener through said container and into each of said rigid members while said rigid members and said container are in a stationary condition, and means for thereafter simultaneously moving said rigid members and said container along a second path of travel while said mechanical fastener applying means applies multiple additional fasteners through said container and into each of said rigid members.

26. The apparatus of claim 25 wherein said adhesive applying means includes means for controlling the application of adhesive to said rigid members.

27. The apparatus of claim 25 wherein said rigid member moving means includes a plurality of laterally spaced support members for supporting said rigid members during movement along said path of travel and air cylinder drive means are mounted on each of said support means for moving said rigid members.

28. The apparatus of claim 25 including means for applying multiple mechanical fasteners through said container as said rigid members and container is being moved along said second path of travel.

29. A process for assembling a container having first and second sections, said first section having a bottom and side flaps, and a plurality of rigid skids secured to the underside of said bottom, said process comprising the steps of aligning a plurality of said skids at a first station, transferring said skids to a second station, applying adhesive to the upper surface of said skids during movement thereof from said first station to said second station, stopping the movement of said skids at said second station, placing said first container section directly on top of said skids, applying one mechanical fastener only into each of said skids and through said first container section for mechanically securing each skid to said container section, and thereafter moving said skids and said container section simultaneously along a path of travel.

30. The apparatus of claim 29 including the step of applying a plurality of mechanical fasteners into each of said skids and through said first container section during movement of said skids in said path of travel.

31. The process of claim 30 including the further step of applying adhesive to said flaps and thereafter positioning said second container section over said glued flaps.

32. The method of claim 31 including the step of applying mechanical pressure to said first and second container sections at the location where said flaps have adhesive thereon, and where portions of said second container section overly said flaps, said mechanical

5

pressure being applied until said first and second container sections are securely interconnected as said adhesive sets.
